William Meier, Cleveland, Ohio, assignor to The
Midland Steel Products Company, Cleveland,
Ohio, a corporation of Ohio.

Application November 21, 1936, Serial No. 112,055

9 Claims. (CL. 78—13)

This invention relates to new and useful improvements in power presses and an object of the invention is to provide means to tilt the dies with respect to the impact member rather than the usual practice of tilting the entire press with respect to the floor to accommodate irregularly shaped work pieces.

Other objects and advantages of the invention will become apparent during the course of the following description.

In the accompanying drawing forming a part of the description and wherein like numerals are employed to designate like parts throughout the several views,

Fig. 1 is a front elevational view of a riveting machine showing the riveting dies tilted at an angle to the vertical to rivet a portion of an automobile side rail,

Fig. 2 is a fragmentary front elevational view showing the riveting dies tilted at another angle with the vertical to rivet another portion of the automobile side rail, and

Fig. 3 is a perspective view of the riveting dies disposed in a vertical position.

Briefly stated the purpose of the invention as herein shown is applied to riveting or welding automobile side rails which have kickups and therefor are of irregular contour. In fabricating automobile frames numerous adjuncts, as for example spring hangers, are secured to the side rails in the region of the kickups.

It has been the practice to provide two riveting machines for the kickup of each side rail, that is, a riveting machine to handle the rear incline of the kickup and another machine for the front incline of the kickup. Each of these machines were bodily tilted at a fixed angle with relation to the floor to accommodate the curve in the kickup whereby the spring hangers and other adjuncts and the adjacent side rail could be disposed at right angles to the riveting or welding dies.

My invention provides a machine having means for tilting the dies to different angles with respect to the vertical, to weld or to head a rivet in any portion of the kickup, to thereby eliminate the employment of a great number of riveting machines.

In the embodiment of the invention herein described the numeral 10 designates a press frame in which is journaled a shaft 11 provided with a pulley 12 connected to a suitable source of power supply. Connected to the shaft 11 is the usual clutch mechanism, not shown, operated through a rod 13 controlled by a clutch pedal 14 to start and stop the press.

The shaft 11 has a cam or crank 15 connected to a link 16 adjustably connected by means of a bolt 19 to an impact member or plunger 20. This impact member has a tongue and groove

sliding connection 21 with guides 22 mounted on the frame 10, these guides defining a fixed path for the reciprocating movement of the impact member 20.

Journaled in the frame 10 is a stout shaft 26 for supporting a die bed or platform 25. This shaft extends rearwardly of the frame 10 and supports a counter-balance 27 which when in vertical position holds a base 30 of the platform 25 in normal horizontal position. On this base 10 30 is suitably mounted a lower die or riveting anvil 31 adapted to accommodate the head of a rivet, and is further provided with an overhanging portion 32 which receives a reciprocable ram or upper die 33 also adapted to accommodate 15 one end of a rivet. Disposed in the overhanging head 32 are spring pressed detents, not shown, for releasably holding the riveting ram 33 in elevated or retracted position. The riveting ram 33 is manually raised and lowered with respect 20 to the lower die 31 by means of a handle 35 which is manipulated to cause the spring pressed detents, not shown, to releasably support the upper die 33.

The extreme upper end 36 of the riveting ram 33 is curved for engagement with an arcuate surface 37 of the impact member 20 whereby, irrespective of the tilt of the upper die 33 with respect to the vertical axis of the impact member 20, the arcuate surface 37 will strike the end 36 of the upper die 33 and move the latter toward the lower die 31 to head a rivet 39 or perform a welding operation therebetween.

The platform 25 is tilted to different angles with respect to the impact member 20 about its axis 26 by means of operator operated tilting mechanism disposed beneath the platform 25. This mechanism comprises an inverted T-shaped lever 40 fulcrumed at 43 and having lever arms 41 and 42, and an upstanding lever arm 44 provided with a ball shaped end 45 loosely received in a socket 46 formed in a lug mounted to the underside of the platform base 30. In order to oscillate the lever 40 a pair of foot treadles 50 and 51 are provided and respectively engage the lever arms 41 and 42 and are pivoted as indicated at 52 to a bracket 53 bolted to the frame 10. A pair of bolts 54 and 55 are adjustably threaded in the bracket 53 for engagement with a lug 56 depending from the die platform base 30 to limit the degree of tilting of the aligned dies 31 and 33 with respect to the impact member 20.

In operation, assume it is desired to head the rivet 39 at the rear end 60 of the kickup 61 of the side rail 62. The operator presses the foot treadle 50 to swing the die platform 25 clockwise about its shaft 26 until the lug 56 strikes the adjustable stop 54 to the position shown in Fig. 1. In this position the upper and lower dies are at right angles to the rear end 60 of the kickup and 60

in alignment with the rivet 39, which will be the proper riveting position to accommodate the downward incline of the rear end 60 of the kickup without the necessity of tilting and maneuvering the heavy auto frame to this relation with the press. In other words, the dies must be tilted to substantially the same angle as that made between the rear end of the kickup and the horizontal. This angle of tilt may be altered by adjusting the screw 54.

The operator then manipulates the trip handle 35 to release the upper die 33 and allow it to drop and rest upon the rivet 39 as shown in Fig. 1. In order to head the rivet 39 the operator exerts pressure on the clutch pedal 14 whereby the cam shaft 11 rotates and causes the impact member 20 to descend and the arcuate surface 37 thereof strikes the end 36 of the upper die 33 to force the latter against the rivet 39 and head the same. Upon the upstroke of the cam shaft 11 the impact member 20 is raised and the operator grasps the handle 35 and raises the upper die 33 with respect to the overhanging head 32 until the detents therein engage the upper die 33 and hold the latter in raised position.

When it is desired to head a rivet 65 disposed toward the front end 66 of the kickup 61, the operator exerts pressure on the foot pedal 51 to swing the die platform 25 counter-clockwise about the shaft 26 until the lug 56 abuts the adjustable stop 55 to the position shown in Fig. 2. In this position the upper and lower dies are tilted to an angle that is substantially equal to the angle made between the front end 66 of the kickup 61 and the horizontal. The rivet 65 is then headed in the same manner heretofore described in connection with the rivet 39.

If the work to be riveted is disposed in a horizontal plane, the die bed 25 is allowed to return to its normal vertical position shown in Fig. 3, and is held in this position by the counter-balance 27.

This apparatus may, for example, also be employed as a punch or welding press, punch dies or welding dies being substituted for the riveting dies, accordingly it will be understood that various changes in the construction and arrangement of the parts may be resorted to without departing from the scope of the appended claims.

50 I claim:

1. In a power press, an oscillatable die bed, a pair of relatively movable dies carried by said bed for accommodating work therebetween, impact means operable to strike one of said dies to effect relative movement between said dies to operate on said work, and means for tilting said die bed to different angles with respect to said impact means.

2. In a power press, an oscillatable die bed, a lower die and an upper die movable with respect to said lower die carried by said bed, power operated impact means separate from said upper die and operable to strike the latter and move the same toward said lower die, and means for supporting said dies and operable to tilt said dies together as a unit at an angle to said impact means.

3. In a power press, a lower die, an upper die manually movable to initial operative position with respect to said lower die, power operated impact means having an arcuate striking surface for striking said upper die to move the latter from initial operative position to final operative position with respect to said lower die, and means

for supporting said dies and operable to tilt said dies to different angles with respect to said impact means, said arcuate striking surface being contoured to strike said upper die in all angular positions of said dies. 5

4. In a power press, an oscillatable die bed, a pair of relatively movable dies carried by said bed, an impact member reciprocable in a fixed path for striking one of said dies to effect relative movement therebetween, and means for tilting 10 said die bed to different angles with respect to said reciprocable impact member.

5. In a riveting machine, a frame, a die supporting bed journaled in said frame, a riveting anvil carried by said bed, a reciprocable riveting 15 ram carried by said bed and cooperating with said anvil to head a rivet therebetween, an impact member reciprocable in a fixed path for striking said ram to head the rivet, and means for tilting said bed, anvil and ram to different angles with 20 respect to said reciprocable impact member.

6. In a power press, an oscillatably mounted die bed, a pair of relatively movable dies carried by said die bed for accommodating work therebetween, power operated means for moving one 25 of said dies toward the other to operate on the work therebetween, and means for tilting said die bed to different angles with respect to the vertical, comprising lever means engageable with said die bed, and operator operated means for operating 30 said lever means to tilt the latter and thus said die bed and dies to an angle with respect to the vertical to accommodate work inclined to the horizontal.

7. In a power press, an oscillatably mounted die 35 bed, a pair of relatively movable dies carried by said die bed for accommodating work therebetween, power operated means for moving one of said dies toward the other to operate on the work therebetween, and means for tilting said die bed to different angles with respect to the vertical, comprising lever means engageable with said die bed, and operator operated means for operating 40 said lever means to tilt the latter and thus said die bed and dies to an angle with respect to the vertical to accommodate work inclined to the horizontal, and means for determining the angle of tilt of said die bed and dies with respect to the vertical. 45

8. In a power press, an oscillatory die bed, a 50 pair of relatively movable dies carried by said bed for accommodating work therebetween, means for moving one of said dies toward the other to operate upon the work, means for tilting said die bed to different angles with respect to the vertical, comprising an inverted T-shaped lever having its stem engageable with said die bed, and a pair of treadles fulcrumed to lie across the arms of the inverted T-shaped lever for swinging said die bed and dies to an angle with respect to 55 the vertical. 60

9. In a power press, a frame, a horizontal shaft journaled therein and having a counter-weight attached thereto, an oscillatory die bed secured to the shaft to hang vertically pendant therefrom to normally overbalance the counterweight and being adjustable to angular positions to either side of the vertical position, upper and lower relatively movable dies carried by the adjustable die bed for receiving work therebetween, and impact means carried by the frame and movable in a fixed path to strike the upper die in all angular positions thereof. 65
